UNITED STATES PATENT OFFICE.

JOSEPH F. LANGTON, OF WALTHAM, MASSACHUSETTS.

DESIGN FOR A SAVINGS-BANK.

SPECIFICATION forming part of Design No. 26,198, dated October 20, 1896.

Application filed September 18, 1896. Serial No. 606,301. Term of patent 7 years.

To all whom it may concern:

Be it known that I, JOSEPH FRANCIS LANGTON, of Waltham, in the county of Middlesex and State of Massachusetts, have invented 5 and produced a new and original Design for a Savings-Bank, of which the following is a full, clear, and exact specification.

Reference is to be had to the accompanying drawings, forming a part of this specification, 10 in which similar characters of reference indicate corresponding parts in both the figures.

Figure 1 is a perspective view of a savings- bank, showing my design; and Fig. 2 is a plan view of the same.

15 The leading feature of my design consists in the miniature representation of a castle in the form of a central tower A, surmounted by

a tower B of less diameter, and surrounded by a series of towers C, C', C², and C³. Minor features of the design are the varying diameters of the towers, each of which is also ornamented near its upper end with a horizontal slot D and vertical slots E, located in different vertical planes and one above the other. The several towers are mounted on a suitable 20 base F.

I claim—

The design for a savings-bank, as herein shown and described.

JOSEPH F. LANGTON.
